UNITED STATES PATENT OFFICE.

FRANZ X. WAGNER, OF NEW YORK, N. Y., ASSIGNOR TO UNDERWOOD TYPEWRITER COMPANY, OF NEW YORK, N. Y., A CORPORATION OF NEW JERSEY.

PAPER-GUIDE FOR TYPE-WRITING MACHINES.

SPECIFICATION forming part of Letters Patent No. 752,131, dated February 16, 1904.

Application filed February 11, 1903. Serial No. 142,850. (No model.)

To all whom it may concern:

Be it known that I, FRANZ X. WAGNER, a citizen of the United States, and a resident of the borough of Manhattan, city, county, and State of New York, have invented certain new and useful Improvements in Paper-Guides for Type-Writing Machines, of which the following is a specification.

My invention relates to paper-guides for type-writing machines, and has for its object to provide simple means for efficiently guiding the paper and holding it in contact with the platen and also for enabling the paper to be fully released when desired.

To this end my invention consists in certain novel constructions and arrangements of parts, as will be fully described hereinafter, and particularly pointed out in the claims.

Reference is to be had to the accompanying drawings, in which—

Figure 1 is a plan of the type-writer platen provided with my improvements. Fig. 2 is a front elevation thereof. Fig. 3 is an end elevation. Fig. 4 is an inverted plan. Fig. 5 is a sectional elevation on line 5-5 of Fig. 4. Fig. 6 is a detail showing the device for throwing the front rail of the platen and the devices carried thereby away from the platen, and Fig. 7 is a detail showing one of the feed-rollers arranged at the rear of the platen and the support of such roller.

A indicates the platen, and A' its shaft, which is journaled in the platen-frame B. At its front portion the platen-frame has a front bar B', movably supported, as will be described hereinafter. On this bar is adapted to slide a sleeve C, having a finger C' arranged to engage the paper at the central portion of the platen. On the front bar B' are further mounted adjustable sleeves D, having set-screws E and carrying brackets D', which support curved paper-guides F. Each of these guides has a roller F' journaled thereto, and the guide, together with the roller, is normally pressed against the platen by a spring F'. (See Fig. 5.) Below the platen and at the rear thereof is located an open-work frame, consisting of a front bar B'', cross-bars B'', and

a rear bar B''. This frame is rigidly connected with the platen-frame B. At the rear of the platen carriers G are loosely mounted, each carrier having at its upper end a loose engagement with a pin H, while near its lower end the carrier has a similar engagement with a screw J, surrounded by a coiled spring K, which has a tendency to throw the lower end of the carrier toward the platen. Below the platen is located a longitudinally-movable bar L, having cut-out portions or cam portions L', which are adapted to engage projections G' on the carriers G. A longitudinal movement of the bar L toward the left in Fig. 4 will therefore operate to throw the carriers G away from the platen. These carriers are provided with feed-rollers O, adapted to engage the platen. The looseness at the pins H and screws J is such that the rollers O can swing not only toward and from the platen, but also at an angle thereto, so that these rollers may accommodate themselves to any unevenness in the platen. The bar L is suitably guided in the frame B, and screws L' may be provided at suitable points to act as additional guides, it being understood that such screws would be alternately at opposite sides of the bar L. As a means of shifting the bar L, I may provide a crank M, having a pin M' adapted to engage a slot L'' of the bar L, while the shaft M' carries a handle N, through the medium of which the operator may shift the bar L lengthwise.

At the front portion of the platen and under the same carriers P are pivoted to the platen-frame, as indicated at P' in Fig. 4, and each of these carriers is provided with a cam projection P', adapted to be engaged by a corresponding portion L'' of the sliding bar L. Each of the carriers P is provided with a roller O' and is normally pressed against the platen by a spring Q.

It will be understood that when the bar L is in the position illustrated by Fig. 4 all the rollers will be in engagement with the platen. If, however, the bar is shifted to the left, the cam portions or actuating portions L' L'' will engage the projections G' P' and swing the

rollers O O' away from the platen, thus releasing the paper. It is desirable that at the same time the guides F and rollers F' should be swung away from the platen. This is effected by the following mechanism: At one end the bar L is provided with a cut-out portion L¹, having an inclined wall. This inclined wall is adapted to engage a finger R', projected from a lever R, which is pivoted at R² and guided by the engagement of a screw S with the walls of the slot R². When the bar L is moved from the position shown in Fig. 4, the lower end of the lever R is swung to the left, (referring to Fig. 3,) and its upper end is therefore moved to the right. This upper end is pivotally connected at T' with a link T, provided with a slot T², engaging a stationary guide U. This link also engages a toe V³ at the lower end of an arm V, which projects from a lever V, fulcrumed at Y' upon another lever Y, which in turn is fulcrumed at Y² upon the platen-frame. This lever Y also forms a carrier for the movable front bar B' and is normally held in the position illustrated by Figs. 3 and 6 by a spring W, which engages a stationary abutment X on the frame. A knob V² is provided on the lever V to facilitate operating same. The toe V³ normally projects into a notch B⁵ of the platen-frame. When the knob V² is pressed downward, the lever V will first rock alone on its pivot Y', so as to disengage the toe V³ from the notch B⁵. Then as soon as the rear end of the lever V below the knob V² engages the lever Y the two levers will move together, swinging about the pivot Y² and causing the front bar B' and the paper-guides C' F F', carried thereby, to move away from the platen. The other rollers O O' will, however, remain in engagement with the platen or the paper. The arrangement described therefore provides means for swinging the paper-guides F F' away from the platen without affecting the adjustment of the other parts. When the operator by moving the handle N shifts the bar L and throws the rollers O O' off the platen, as described, he also through the medium of the lever R and link T moves the lever V, as will be understood by reference to Fig. 3, and causes the front bar B', with the parts carried thereby, to be swung in the same manner as they would be by the manual depression of the knob V².

I desire it to be understood that the particular form of construction shown in the drawings is only one example of my invention and that various modifications may be made without departing from the nature of my invention.

What I claim as new, and desire to secure by Letters Patent, is—

1. The combination, with the platen and pressure-exerting devices adapted to engage the same, of a longitudinally-movable bar for throwing the said pressure-exerting devices

off the platen, a lever arranged to be swung transversely by the longitudinal movement of the said bar, and a paper-guide arranged adjacent to the platen and adapted to be swung away therefrom when the said lever is operated by the movement of the said bar. 70

2. The combination, with the platen and pressure-exerting devices adapted to engage the same, of means for throwing said pressure-exerting devices off the platen, a paper-guide movable toward and from the platen, and means for operating said paper-guide, said means being in loose engagement with the means for throwing the pressure-exerting device off the platen, so that the paper-guide 80 may be operated independently of the said pressure-exerting devices. 75

3. The combination, with the platen, of a lever fulcrumed thereon, a paper-guide carried by said lever, and another lever fulcrumed 85 upon the first-named lever and in locking engagement with the platen-frame, said second lever being capable of an initial independent movement to disengage it from the platen-frame. 90

4. The combination, with the platen and its frame, of a lever fulcrumed on said frame, a front bar carried by said lever, a paper-guide supported by said front bar, and an auxiliary locking-lever fulcrumed upon the first-named lever and normally in locking engagement with the platen-frame. 95

5. The combination, with the platen and its frame of a plurality of roller-carriers arranged adjacent to the platen and having their rollers 100 in longitudinal alinement with each other, each roller-carrier being capable of an independent movement toward and from said platen, said carriers being further capable of an independent oscillating motion so as to bring one end 105 or the other of each roller nearer to the platen-surface, and means for throwing all of said carriers away from the platen. 110

6. The combination, with the platen and its frame, of a plurality of carriers loosely mounted on said frame so as to be independently movable toward and from the platen, a plurality of alining rollers journaled on said carriers and extending parallel with the platen, said carriers being capable of independently swinging in such a manner as to bring one end or the other of each roller nearer to the platen-surface and means for throwing said carriers away from the platen. 115

7. The combination, with the platen and its frame, of pressure-exerting devices movable toward and from the platen, a sliding bar for throwing said pressure-exerting devices off the platen, said bar being provided with an inclined surface, a transversely-movable lever 120 arranged to be operated by engagement with said inclined surface of the sliding bar, and a paper-guide movable toward and from the platen and arranged to be swung away from the platen by the movement of said lever. 125 130

8. The combination, with the platen and its frame, of a rigid carrier, a roller having both of its ends journaled on said carrier, the carrier and roller being capable of moving toward and from the platen and being further capable of an oscillating motion so as to bring one end or the other nearer to the platen-surface, the axis of the roller being always in the same relation to the carrier during all of its motions

and means for throwing said carrier and roller away from the platen.

In testimony whereof I have signed my name to this specification in the presence of two subscribing witnesses.

FRANZ X. WAGNER.
